United States Patent Office.

O. D. CHAPMAN, OF CHICAGO, ILLINOIS.

Letters Patent No. 77,957, dated May 19, 1868.

IMPROVEMENT IN TUBE-WELLS.

The Schedule referred to in these Letters Patent and making part of the same

TO ALL WHOM IT MAY CONCERN:

Be it known that I, O. D. CHAPMAN, of Chicago, in the county of Cook, in the State of Illinois, have invented a new and useful Improvement in Tube-Well; and I do hereby declare that the following is a full and exact description thereof, reference being had to the accompanying drawings, and to the letters of reference marked thereon, making a part of this specification, in which—

Figure 1 is an elevation of my invention.

Figure 2, a sectional elevation of the same.

The nature of my invention consists in making a series of chambers between the tube and wire cloth, and a chamber between the cloth and the outer perforated plate, for the purpose of securing the greatest possible amount of filtering-surface.

In order to give a correct understanding of my invention, I have marked corresponding parts with similar letters, and will now give a detailed description.

A represents the lower section of a tube-well, having holes B through it, and attached to a point, C, in the usual manner. d represents a series of metal bands put around the tube A between the holes, and soldered fast, for the purpose of keeping the wire cloth E from coming in contact with the tube A, as seen at fig. 2. The bands d should not be so wide as to take up any considerable portion of the filtering-surface of the cloth E, and should only be thick enough to form a passage for water to run freely between the cloth and the tube, and enter the holes B. This arrangement obviates the necessity of grooving the tube A, for securing a proper filtering-surface through the cloth, E. And as the bands d are soldered to the tube A, and the cloth E to the bands, there is no liability of their becoming detached. A wire, F, is wound spirally over the said cloth for the purpose of forming an outer chamber between it and an outside perforated plate, G. In the drawings, at fig. 1, a portion of the plate G is represented as broken away, for the purpose of showing more clearly the wire cloth and bands underneath, but is intended to cover the cloth, E, and be fastened securely to tube A, to prevent it from becoming detached when said tube is being driven.

It will be seen, from this description, that the wire cloth E has a much greater filtering-surface, aside from that taken up by the bands d and wire, F, than the area of four rows of holes B, by which means a sufficient quantity of water will enter said holes, notwithstanding the meshes in the cloth become half filled with sediment.

What I claim, and desire to secure by Letters Patent of the United States, is—

The combination of the bands d, wire cloth E, spiral wire F, and perforated plate G, with tube A, substantially as and for the purpose set forth.

O. D. CHAPMAN.
